UNITED STATES PATENT OFFICE.

HENRY G. VOIGHT AND CHARLES J. CALEY, OF NEW BRITAIN, CONNECTICUT, ASSIGNEES
TO RUSSELL & ERWIN MANUFACTURING COMPANY, OF NEW BRITAIN, CONNECTICUT, A
CORPORATION OF CONNECTICUT.

INDICATOR FOR DOOR-LOCKS.

No. 884,996.

Specification of Letters Patent.

Patented April 14, 1908.

Application filed November 29, 1907. Serial No. 404,292.

To all whom it may concern:

Be it known that we, HENRY G. VOIGHT and CHARLES J. CALEY, citizens of the United States, residing at New Britain, county of 5 Hartford, Connecticut, have invented certain new and useful Improvements in Indicators for Door-Locks, of which the following is a full, clear, and exact description.

This invention relates to improvements in 10 indicators for door locks, to inform, by the sense of touch, any person desiring to enter a room, whether the door has been locked from the inside. In this connection, it is of particular value when applied to corridor 15 doors where only a dim light prevails. It has great value in connection with hotel bedroom doors, where an effort to open the door of an occupied room might disturb the occupant.

20 In the drawings Figure 1 is a section of a door fitted with our improved indicating device. Fig. 2 is a view of the inner side of the indicator. Fig. 3 is a longitudinal section of the same. Fig. 4 is a front view of the same. 25 Fig. 5 is a view of the frame of the indicator, with the other parts detached. Fig. 6 is a side view of the operating button detached. Fig. 7 is a view of the locking sleeve, detached. Fig. 8 is a side view of the end closure for the locking sleeve, detached. Fig. 9 30 is a relatively enlarged sectional view of the upper half of the indicator, assembled.

1 represents a portion of a door.

2 represents the casing for a dead-bolt (not 35 shown).

3 is a bolt-operating device, of any desired construction, in this instance a thumb-turn.

4 is a bolt actuating spindle, in this instance having a cross section corresponding 40 in outline to a gear. This spindle is turned by the thumb turn 3.

Thus far the mechanism represents a well-known dead-bolt of conventional form. The indicating mechanism comprises a casing or frame 5, which may be suitably secured to the outside of a door in any well-known manner. Projecting through the front of the casing 5 is a button or finger-piece 6, by the feeling of which a person who desires to enter 45 the room may ascertain whether the door is locked, so as to avoid the necessity of disturbing the occupant. In the particular form shown, if the button 6 is free to be pushed in, it indicates that the door is un-

locked, whereas, on the other hand, if the 55 button 6 is held rigid, it would indicate with equal certainty that the door is locked.

The construction in its preferable form is as follows: 7 is a locking sleeve secured, for example by a screw 6^a, to the rear of the button 6. The sleeve 7 has an intermediate partition to furnish a proper bearing for the button 6 and screw 6^a. This sleeve 7 extends forwardly of the partition and in this forward extension is an angular slot 9, one portion of said slot extending longitudinally of the sleeve, the other portion extending transversely thereof. To the rear of said partition is also an extension which carries a closure 8. This closure may be secured in any 60 desired way to the sleeve 7, but the preferable construction comprises two radial arms on the closure which extend into recesses 65 in the rear edge of the sleeve 7 so that by swaging down the edges of the said recesses 70 75 10 (see Fig. 1) the closure will be securely connected to the sleeve, not only so as to prevent endwise removal, but also so as to lock the plate 8 and sleeve 7 together for rotary movement.

In the central part of the closure 8 is a 80 passage of suitable outline to receive the end of the spindle 4 so that when the spindle is turned the sleeve 7 will be turned. The casing or frame 5 is provided with an inwardly projecting sleeve 11, the inner edge of which is turned in slightly to form an abutment for a spring 12. That part of the push button 6 within this sleeve 11 is reduced somewhat in diameter to provide a space for 85 said spring 12. The extreme inner end of the button 6 is preferably slabbed off to fit in the partition in the sleeve 7 so that the screw 8 may be more firmly set down, since by this means the parts 6 and 7 are held 90 against independent rotation. This, however, is not essential; in fact, instead of a screw 7, the inner end of the button 6 might be riveted in place back of the partition in 95 the sleeve.

100 14 is a pin carried by the frame 5 and projecting into the slot 9. In the particular arrangement shown, this pin 14 will stand in line with the longitudinal extension of slot 9 when the door is unlocked (see Fig. 3) with 105 the result that under these conditions the push button 6 may be readily pushed in against the pressure of spring 12. When,

however, the door is locked, the sleeve 7 will be turned so that the end of the pin 14 will stand in the transverse portion of slot 9 in which position the button 6 cannot be pressed in. Since this turning of the sleeve 7 is accomplished when the door is locked, it follows that at such time the button 6 will be held rigid and an outsider will know that the door has been locked and need not disturb the occupant of the room by any effort to gain admittance. Obviously the action of the button might be reversed by simply having the pin stand in the transverse portion of slot 9 when the door is unlocked, in which event when the button is rigid the door is unlocked, and when yielding it indicates that the door is locked. This mere reversal of operation is so obvious as to require no illustration.

What we claim is:

- 20 1. In an indicator for door locks, a frame having a central tubular aperture, a push button therein, a sleeve carried at the inner end of the push button, said sleeve having an angular slot and a pin carried by said frame entering said slot, and means for connecting said push button with a door locking device.
- 25 2. An indicating mechanism for a door locking device, comprising a case having a central tubular aperture, a push button slide-
30 able therein and guided thereby, a spring space between said parts, a spring therein, a sleeve carried by said push button, and hav-

ing an angular groove therein, a pin carried by said frame and entering said groove, and means for connecting said sleeve and push 35 button to said door locking mechanism.

3. An indicating mechanism for a door locking device, comprising an operating rotatable spindle, a sleeve slidable thereon but rotatable therewith, a push button carried by 40 said sleeve, a frame or case surrounding said push button, means for normally pressing said push button outwardly, an extension from said sleeve having a groove therein, a portion of said groove being in the line of 45 longitudinal movement of the button, another portion of said groove being in the line of rotary movement of said sleeve, and a pin carried by the frame entering said groove.

4. In an indicator for door locks, one part 50 including a frame having a guide-way therein, another part including a push button adapted to said guide-way, said parts being movable relatively to each other, one of said parts having an angular locking slot or pas-
55 sage, the other part having a projection or pin entering said slot, and means for connecting said push button part with a door-locking device.
